(57) **CLAIM**

I claim the ornamental design for the belt with expandable pouch, as shown and described.

DESCRIPTION

FIG. 1 is a front elevational view of an belt with expandable pouch.

FIG. 2 is a front view of a pouch according to the present invention, wherein the belt has been removed for convenience of illustration.

FIG. 3 is a rear view of a pouch according to the present invention, wherein the belt has been removed for convenience of illustration.

FIG. 4 is an isometric view showing the back, top and side of an belt with expandable pouch.

FIG. 5 is a top down view of an empty pouch according to the present invention, wherein the belt has been removed for convenience of illustration; and,

FIG. 6 is a bottom up view of an empty pouch according to the present invention, wherein the belt has been removed for convenience of illustration.

The broken lines are for illustrative purposes only and form no part of the claimed design.
